UNITED STATES PATENT OFFICE

HENRY FORD, OF DEARBORN, MICHIGAN, ASSIGNOR TO FORD MOTOR COMPANY, OF DEARBORN, MICHIGAN, A CORPORATION OF DELAWARE

STARTING GEAR

Application filed September 8, 1930. Serial No. 480,446.

The object of my invention is to provide a starting gear of simple, durable and inexpensive construction especially adapted for use in starting automobile engines.

5 Still a further object of my invention is to provide a starting gear incorporating a novel overrunning clutch disposed between the pinion gear and the starting motor so that the gear may be positively driven by the starting motor to crank the engine but will be allowed to overrun the starting motor when the engine starts and thereby drives the pinion.

10 Still a further object of my invention is to provide a starting gear which is manually initially urged into engagement with the engine flywheel ring gear and which is automatically moved into full engagement with the ring gear after the initial movement. Inversely, my improved starting gear is both 15 automatically and manually shifted out of engagement with the engine flywheel when the latter rotates under its own power.

20 Still a further object of my invention is to provide a starting gear having spiral teeth so that the device will be exceptionally quiet in operation to thereby make it especially suitable for use in automobiles where noise is 25 objectionable.

30 Still a further object of my invention is to provide a starting pinion directly mounted on a plain bearing to thereby secure the pinion in perfect alignment and to allow the use of an exceptionally small pinion thus providing a high gear ratio between the starting 35 motor and the engine.

With these and other objects in view, my invention consists in the arrangement, construction, and combination of the various 10 parts of my improved device, as described in the specification, claimed in my claims, and illustrated in the accompanying drawing, in which:

Figure 1 shows a plan view of my improved device, parts of the engine flywheel housing and starting motor being broken away to better illustrate the construction.

Figure 2 shows a sectional view through 5 my improved starting gear, illustrating the 0 overrunning clutch, and

Figure 3 shows a sectional view taken on the line 3—3 of Figure 2.

Referring to the accompanying drawing, I have used the reference numeral 10 to indicate generally an engine flywheel housing in which a conventional flywheel 11 is rotatably mounted. A flywheel ring gear 12 is secured to the periphery of the flywheel 11, this ring gear being preferably formed from a relatively narrow steel ring bolted to the edge of the flywheel. However, if desired, the ring gear 12 can be formed integral with the flywheel, the teeth thereon being machined in the material of the flywheel. The ring gear has a plurality of spiral gear teeth 13 machined in its periphery, the spiral of the teeth being governed by the direction of rotation of the engine.

My improved starting motor consists of a tubular shell 14 which is secured to a flange 15 which forms one end of the motor and which is fastened to the flywheel housing 10 by suitable cap screws 16. The center portion of the flange 15 is dished away from the motor so that it projects into the flywheel housing and a bearing 17 is formed in the center of this dished portion to rotatably receive one end of an armature shaft 18. A conventional armature 19 is fixedly secured to the shaft 18 which armature is electrically 20 rotated in the ordinary manner.

I have provided a starting motor switch 20 which is fastened to the upper side of the shell 14. The switch 20 is operated by a push rod 21 which extends upwardly through the floor boards of the car where a button 22 is fastened thereto in position to be operated by the driver's foot. When the button 22 is depressed it operates the switch 20 in the conventional manner thereby operating the starting motor until the button 22 is released.

The armature shaft 18 is provided with a splined section 23 adjacent to the armature 19 and spaced from bearing 17, upon which portion a correspondingly splined sleeve 24 is reciprocally mounted adjacent to the armature and the forward end of the sleeve 24 is provided with a radial flange 25 extending forwardly a short distance. I have provided a pinion gear 27 rotatably mounted on that 100

portion of the shaft 18 between the splines 23 and the bearing 17 which gear is provided with a sleeve 28 which extends rearwardly abutting the end of the flange 25. A sleeve 40 extends from the sleeve 28 and encloses the flange 25. A locking ring 29 is secured in a suitable groove in the sleeve 40 so that although relative rotation is allowed between the sleeve 28 and the flange 25 still the members will be locked against relative reciprocation.

An annular chamber 26 is provided between the splines 23 and the abutting portions of the sleeve 28 and flange 25 in which chamber an expanding clutch is provided which locks the sleeve and flange together when the flange tends to overrun the sleeve. This clutch consists of a helical band 30 having one end anchored at 31 in the flange 25 and the other end extending into the sleeve 28. It will be noted from Figure 3 that this end of the band 30 is beveled at 32 to receive a ball 33 which bears against the hub of the pinion 27. A ball type overrunning clutch is thus provided which operates to energize the band thereby expanding same in the chamber 26 when the flange 25 tends to drive the pinion 27.

The ball 33 locks the free end of the band 30 in the sleeve 28 thereby forcing the band to unwind and tightly engage the sleeve member. Thus, the pinion 27 is driven by the friction of the band and not by the action of the ball 33 alone. Of course, the band releases or uncoils in the chamber 26 when the pinion 27 tends to overrun the starting motor so that the engine is free to rotate the pinion 27 without having to drive the starting motor armature.

Means are provided for initially shifting the pinion gear 27 into mesh with the ring gear 12 which consists of a lever 34 pivotally mounted at 35 in the shell 14, the lower end of which lever is forked at 36 to engage an annular groove 37 formed in the exterior of the sleeve 28. When the upper end of the lever 34 is pressed downwardly it manually shifts the pinion 27 into engagement with the teeth 13 to thereby manually connect the gearing. The upper end of the lever 34 is provided with an eye through which the rod 21 extends and a coil spring 38 bears against this portion of the lever to resiliently urge same against a pin 39 which extends through the rod. The upper end of this spring is anchored to the rod 21 just below the car floor boards so that when the rod 21 is pressed, the pinion 27 is not positively shifted into engagement with the ring gear 12 but is rather resiliently urged into this position by the spring 38.

A second coil spring 41 is disposed between the switch 20 and the lower end of the pin 39 so that the rod 21 is resiliently urged at all times to position where the switch 20 is dis-

engaged and the pinion 27 is out of mesh with the gear 12. An important feature in connection with this device arises because of the spiral of the teeth 13 and pinion 27. After the pinion is initially brought into engagement with the gear 12 the torque of the armature automatically draws the pinion into full engagement. Inversely, when the engine starts to operate under its own power, the spiral of the teeth 13 automatically forces the pinion 27 out of engagement even though the spring 38 is still urging it into the engaged position. The pinion 27 is, of course, free to overrun the armature so that no damage can be done to the starting motor even though the pinion is forced to rotate at high speed while it is being disengaged.

To operate my improved device, the button 22 is pressed thereby initially shifting the pinion 27 into mesh with the ring gear 12 and then completing the starting gear motor switch 20 to thereby start the motor. The torque from the shaft 18 is transmitted through the band 30 to the sleeve 28 to thereby drive the pinion and thus rotate the engine flywheel to start the motor. It will be noted that if upon the initial application of the button 22 the pinion is not in position to enter between the gear teeth 13 then the spring 38 will be compressed to allow the armature to rotate the pinion to position where it will become engaged thereby allowing the spring 38 to urge it into mesh.

The novel features in connection with this device arise for the reason that the spiral teeth on the ring gear and pinion are of such angle that the pinion is thrown out of engagement when the flywheel overruns the starting motor armature. Further, the spiral gear teeth combined with the firm mounting of the pinion 27 on the bearing 17 produce an exceptionally quiet driving gear. Still further, with this device I am enabled to provide a pinion drive gear of very small pitch diameter to thereby secure a high ratio of reduction between the starting motor and the flywheel. Still further, the overrunning clutch incorporated in this device provides a positive drive between the starting motor armature and the pinion 27 which tests prove will last the life of the engine and require very little attention.

Some changes may be made in the arrangement, construction, and combination of the various parts of my improved device, without departing from the spirit of my invention, and it is my intention to cover by my claims, such changes as may reasonably be included within the scope thereof.

I claim as my invention:

1. In the device of the character described, an engine flywheel having a spiral toothed ring gear formed thereon, a starting motor upon the driving shaft of which a spiral toothed pinion is rotatably and reciprocally

mounted so as to mesh with said ring gear when reciprocated to one of its positions, a switch mounted upon said starting motor having a reciprocable rod extending radially therefrom to actuate same, a lever pivotally mounted on said motor having one end disposed adjacent to said rod and the other connected to said pinion whereby oscillation of said lever will reciprocate said pinion into mesh with said ring gear, and a compression spring disposed around said rod having its outer end secured thereto and its inner end abutting said lever, whereby upon depressing said rod said pinion will be reciprocated into mesh with the ring gear and upon said engine starting under its own power said pinion and lever will be returned to their inoperative positions independently of the position of said rod.

2. In a device of the character described, an engine flywheel having a spiral toothed ring gear formed thereon, a starting motor upon the driving shaft of which a spiral toothed pinion is rotatably and reciprocally mounted so as to mesh with said ring gear when reciprocated to one of its positions, an overrunning clutch operatively connecting the starting motor shaft and said pinion effecting a unidirectional drive, whereby the motor may drive the pinion and the pinion may overrun the motor, a switch for said motor having a reciprocable rod extending therefrom to actuate same, a lever pivotally mounted on said motor having one end disposed adjacent to said rod and the other connected to said pinion whereby oscillation of said lever will reciprocate the pinion into mesh with said ring gear, and resilient means disposed between said rod and lever whereby depression of said rod to actuate the switch will resiliently urge said pinion into engagement with the flywheel and reciprocation of the pinion out of mesh may be accomplished by said spiral ring gear independently of said rod.

3. In a device of the character described, an engine flywheel having a spiral toothed ring gear formed thereon, a starting motor upon the driving shaft of which a spiral toothed pinion is rotatably and reciprocally mounted so as to mesh with said ring gear when reciprocated to its outward position, an overrunning clutch operatively connected between the starting motor shaft and said pinion effecting a unidirectional drive whereby the motor may drive the pinion and the pinion may overrun the motor, a switch for said motor having a reciprocable rod extending diagonally and upwardly therefrom adapted to be directly actuated by the vehicle operator's foot to actuate the switch, a lever pivotally mounted on said motor having one end disposed around said rod and the other connected to said pinion whereby reciprocation of said rod will reciprocate said pinion into

and out of mesh with said ring gear, a spring disposed around said rod having one end thereof secured to the rod and the other abutting said lever whereby the pinion may be both resiliently urged into engagement with said flywheel and allowed to be reciprocated out of mesh with said ring gear when the latter is operated by the engine.

HENRY FORD.
